Attorney

UNITED STATES PATENT OFFICE.

BARON HENRY SCOTFORD, OF ATLANTIC CITY, NEW JERSEY.

DRESS.

Application filed July 30, 1920, Serial No. 400,068. Renewed April 12, 1922. Serial No. 551,831.

To all whom it may concern:

Be it known that I, BARON HENRY SCOTFORD, a citizen of the United States of America, residing at Atlantic City, in the county 5 of Atlantic and State of New Jersey, have invented a new and useful Improvement in Dresses, of which the following is a specification.

My invention relates to dresses and particularly to dresses made of detachable sections 10 or parts and designed to be worn principally by girls and children.

The objects of my invention are to provide a simple, useful and attractive dress which 15 is made in sections detachably fastened together, which may be easily and quickly put on or taken off and conveniently handled in laundering, and which consists of a minimum number of parts or sections, each of 20 unusually simple outline and design.

In the accompanying drawing, wherein 25 two embodiments of my invention are illustrated, and wherein similar numerals refer to like parts in the several views,—

Figure 1 is a front elevational view of the preferred form of dress, as it appears when worn,

Figure 2 is a back elevational view of a modified form of dress, in assembled condition,

Figure 3 is a plan view of one of the dress sections of the form of dress illustrated in Fig. 2,

Figure 4 is a similar view of one of the 35 dress sections of the preferred form of dress shown in Fig. 1, and

Figure 5 is a like view of the belt section.

The dress which constitutes my invention preferably consists of three parts or sections.

Two of these sections are identical in shape and together form the dress proper; the third section acts as a belt. The manner of arrangement of the sections when combined to form a dress is shown in Figures 1 and 2.

The dress sections are of the general form and configuration illustrated in Fig. 3 or Fig. 4, while the belt section is of the form illustrated in Fig. 5.

My sectional dress may be made of any 50 suitable fabric or other material, such as cotton, linen, silk, etc. The belt section may or may not be of the same material as the other sections. Each of the two main dress sections consists of an elongated, relatively

narrow strip or piece of material 1 of general panel shape. It may be made in two parts detachably connected to each other by buttons, snap fasteners, or other suitable means at the median line or portion 2, but I prefer to have each section 1 made of a single piece of material.

The dress section 1 may be of uniform width throughout its length, but it will be understood that these relative dimensions may be varied at will as the design of the 55 dress is changed, so long as the section or panel is symmetrical from its median or shoulder portion 2 to its end portions 3.

In the form of dress illustrated in Figs. 2 and 3 the dress sections are of uniform or substantially uniform width. The preferred forms of dress, however, have one or both 60 sides of each dress section concaved to provide a relatively narrow waist and shoulder portion for the garment, Figs. 1 and 4 illus-

trating an example of this type of dress sections. The latter form usually is made without a sleeve. In either form of dress the shoulder portion may be narrowed to suitable or desired width with respect to the rest 70 of the dress by means of gathers, plaits or tucks.

In the modified form of dress shown in Figs. 2 and 4, the dress section 1 is provided at its middle portion 2 with a laterally-projecting wing 4, which, when the dress is assembled, forms an extended arm or shoulder portion presenting the appearance of a short sleeve when the dress is in use. This 75 sleeve-forming wing portion may be integral with the section 1 or may be cut out separately and fastened thereto permanently by sewing or detachably by snap fasteners or other suitable means.

If a sleeveless dress is desired, the shoulder or sleeve portion 4 80 may be dispensed with.

Each dress section 1 is provided along its edges at and near each end with devices, preferably snap fasteners 5, 5', by which, when the section is folded over upon itself 85 from end to end, the two ends may be detachably secured together, members 5' of the snap fasteners engaging complementary members 5 at the opposite end of the dress section 1.

The belt section 7, as shown, consists of a 90 straight strip of fabric of uniform width, but obviously the shape of the belt between

its ends may be varied to suit the particular design or pattern of dress with which it is used and of which it forms a part, so long as the two ends of the belt are of the same 5 width, or substantially so.

The belt section 7 is also provided with one or more buttons, snap fasteners, or other suitable devices 11 by means of which the ends of the belt may be fastened together.

10 The manner of applying and wearing the dress which forms the subject-matter of my invention is made clear in Fig. 1. To put the dress on, one of the dress sections 1 is laid or draped over one shoulder of the 15 wearer, with its median portion on the shoulder and the two ends hanging free, one at the front and the other at the back of the wearer. These ends are then drawn together and fastened on the outside and in- 20 side of the lower limb of the wearer, so that the limb projects through the fastened ends, provision therefor being made by suitably spacing the fastening devices, as indicated in Figs. 1 and 4, to form a leg opening 10.

25 The section 1 is thus draped diagonally across the body. The second section is similarly placed, with its middle portion on the other shoulder, and drawn diagonally across the body, crossing the first section at both 30 the front and back of the wearer, its ends being in turn brought together and fastened in like manner about the limb of the wearer.

The belt section is then placed about the body of the wearer at or near the waist line, 35 so that it encircles both of the diagonally disposed and crossed dress sections 1. The belt section 7 may also be detachably fastened to one of the dress sections after it is in place, or before its ends have been 40 brought together, by means of a snap fastener 8, 8', or by some other suitable device. When a snap fastener is employed, one of its members 8' is secured to the belt and the other member 8 to one of the dress sections. 45 The ends of the belt may be connected by any suitable fasteners, such as buttons 11, or snap fasteners.

The manner of wearing the form of dress illustrated in Figs. 2 and 3 is slightly different, although the manner of putting it on is practically the same. In this form the lower limb does not go through the dress between the meeting ends of the dress sections, but the ends are drawn together and fastened at their ends throughout their entire width on the outside of the lower limb of the wearer, the limbs projecting between and through the parts of the folded-over sections on the inside and just above the 55 connected ends. The ends of the dress sections may be fastened together along their lower ends at the outer side or left unfastened as desired, the dress usually having sufficient fullness to make the fastening at 60 65 this point unnecessary.

A dress thus formed is of a character mainly adapted to be worn by a child or young girl. The form shown in Fig. 2 is usually intended to be worn with bloomers, tights, or some other garment of a similar nature, but the use of such undergarments is not necessary where the dress has sufficient fullness, especially if the fullness is sufficiently great in the bottom or skirt portion of the dress sections. The required or desired fullness may be obtained either by making each of the dress sections with plaits throughout its entire length or at its two end portions or at its shoulder portion, or by making the dress section plain but of sufficient width at each end to give the desired fullness at the bottom or skirt portion. 70

If desired, the two dress sections 1 may be attached by a permanent or detachable 75 fastening device 12, and the two sections put on together instead of separately, should the 80 wearer prefer to do so.

I claim:—

1. A dress comprising a plurality of separate sections detachable from one another throughout their length and crossing one another in the region of the waist line of the wearer, and a section encircling said first-mentioned sections near their point of crossing for detachably retaining said sections in position. 90

2. A dress comprising a plurality of separate longitudinal sections detachable from one another throughout their length and crossing one another at the front and back 100 of the dress, each of said longitudinal sections extending the full length of the dress, and means for detachably retaining said dress sections in position.

3. A dress comprising a plurality of longitudinal sections crossing one another in the region of the waistline, said sections diverging from one another above and below the point of crossing to form shoulder portions and leg or skirt portions, respectively, 110 and means for holding said sections in crossed relation.

4. A dress comprising a pair of longitudinal sections disposed diagonally across one another, each of said sections being folded 115 over upon itself from end to end, means for detachably securing the opposite ends of each dress section together, and means for detachably securing said dress sections to one another. 120

5. A dress comprising a pair of dress sections and a belt section, the dress sections being disposed diagonally across one another and the belt section encircling both of said dress sections near their point of crossing, each of said dress sections consisting of an elongated strip of material folded over upon itself from end to end, and means for detachably securing the opposite ends of each folded section together. 125

6. A dress comprising a pair of dress sections and a belt section, the dress sections being disposed diagonally across one another and the belt section encircling said dress sections near their point of crossing, each of said dress sections consisting of an elongated strip of material folded over upon itself from end to end to form a looped shoulder portion, waist portions, and end or skirt portions, and means for detachably 10 securing the opposite ends of each of the folded sections together, encircling the leg of the wearer.

BARON HENRY SCOTFORD.
